UNITED STATES PATENT OFFICE.

WALTER A. OLSON, OF TWIN VALLEY, MINNESOTA.

MOTOR-DRIVEN SLEIGH.

Application filed July 19, 1927. Serial No. 206,955.

The present invention is directed to improvements in motor driven sleighs.

The primary object of the invention is to provide a device of this character so constructed that the sleigh will be propelled across the ice during the rotation of a motor driven propeller, the construction being such that the occupant of the sled can conveniently control the movement of the propeller as well as the guiding of the sleigh.

Another object of the invention is to provide a device of this character so constructed that the occupant will be protected against cold and winds.

15 In the accompanying drawing:

Figure 1 is a side elevation of the device.

Figure 2 is a top plan view thereof.

Figure 3 is a longitudinal sectional view.

Figure 4 is a perspective view of one of the 20 front runners.

Referring to the drawing, 1 designates side sills which are held in spaced parallel relation by cross bars 2, there being bottom boards 3 connected to the cross bars 2 as well as

25 the end bars 4. It will be observed upon reference to Figure 1 that the bottom boards 3 are turned upwardly and are maintained in such position by the struts 5 which have their outer ends connected to the end bars 4 and their rear ends connected to the side sills 1.

30 Mounted between the sills 1 is a frame 6 which supports the explosive engine 7, of any well known type, the shaft thereof having a propeller 8 carried thereby which, when in motion, will obviously draw the sleigh across the ice or snow.

Secured to the boards 3 adjacent the forward ends thereof are front runners 8 which consist of a pair of blocks 9 and 10 and between which is secured a plate 11, the sides of the plates being projected beyond the sides of the blocks to provide flanges 12, which will obviously prevent the runners from entering the snow to any appreciable depth, the flanges having their forward ends turned upwardly, as at 13, in order to permit the runners to slide freely.

Secured to the rear bar 4 are brackets 14 and to which are pivotally connected knuckles 15, said knuckles being secured to the upper surfaces of the rear runners 16, said runners being pivotally connected at their rear ends by a bar 17. In this manner the runners 16 may be shifted to guide the sleigh. In order

to guide the sleigh a link 18 is provided and 55 has its rear end pivotally connected to the bar 17 and its forward end pivotally connected, as at 19, to the bar 4, there being an arm 20 carried by the forward end of the lever 18 into which is connected a link 21, 60 said link having its forward end pivotally connected to the lever 22, which is conveniently located with respect to the seat 23 located in the cab 24, which is suitably mounted upon a pair of the bars 2, said cab having 65 doors 25 and has its forward portion tapered in order to offer very little resistance to the wind in the travel of the sleigh. The bars 25, as well as the sides of the cab, are provided with glass panels 26 in order that the 70 occupant of the sleigh can observe the course to travel.

Any suitable means can be connected with the engine in order that the same can be controlled from the occupants of the cab.

75 It will be obvious that when the propeller 8 is rotated that the power derived therefrom will propel the sleigh across snow or ice.

Intermediate sills 27 are supported by the 80 bars 2 to aid in bracing the sleigh.

Having thus described the invention, I claim:

1. A sleigh comprising side sills, cross bars connecting the side sills, bottom boards connected to the cross bars, said bottom boards 85 having their forward ends turned upwardly, and brace bars connecting the forward ends of the bottom boards and side sills to maintain them in their upturned position, a frame supported by the side sills, a motor supported 90 by the frame and having a propeller fixed to its shaft, front and rear runners supported beneath the bottom boards, and means for guiding the rear runners.

2. A sleigh comprising side sills, cross bars 95 connecting the side sills, boards secured to the cross bars, brackets carried by the rear ends of the bottom boards, knuckles pivotally connected with the brackets, a cross bar pivotally connecting the rear ends of a pair of 100 runners which are fixed to said knuckles, a link having its rear end pivotally connected to the cross bar, said link being pivotally connected with the sleigh, and an arm for swinging the link to guide the rear runners. 105

In testimony whereof I affix my signature.

WALTER A. OLSON. [L. s.]
